M. BLUMENTHAL

WATERPROOF CONCRETE PILE

Filed Nov. 7, 1919

Maurice Blumenthal
Inventor
By his Attorney
A. Gustaf Hande

UNITED STATES PATENT OFFICE.

MAURICE BLUMENTHAL, OF BROOKLYN, NEW YORK.

WATERPROOF CONCRETE PILE.

Application filed November 7, 1919. Serial No. 336,263.

To all whom it may concern:

Be it known that I, MAURICE BLUMENTHAL, residing at Brooklyn, in the county of Kings and State of New York, have invented certain new and useful Improvements in Waterproof Concrete Piles, of which the following is a specification.

This invention relates to a means of waterproofing concrete piles and the like.

10 An object of this invention is to provide means whereby concrete piles, such as are made within the earth, are rendered waterproof.

15 A more detailed object is to provide means whereby concrete piles made within the earth are provided with a waterproof coating or jacket adapted to save and protect the concrete material from the evil effects of water or of such constituents of 20 the surrounding earth as may be harmful to the concrete material.

25 A further object is to provide a suitable coating material wherewith to render the concrete piles proof against water or other mediums likely to attack the pile from without.

30 A further object is to provide an improved process by which to apply waterproof coatings to concrete piles and the like.

35 Other objects and aims of the invention, more or less specific than those referred to above, will be in part obvious and in part pointed out in the course of the following description of the elements, combinations,

40 arrangements of parts and applications of principles, constituting the invention; and the scope of protection contemplated will be indicated in the appended claims.

45 In the accompanying drawings which are to be taken as part of this specification, and in which I have shown merely a preferred form of embodiment of the invention:

Figure 1 is a vertical transverse sectional view showing a pile in course of construction in accordance with the provisions of this invention.

Figure 2 is a similar view of the completed pile.

Figure 3 is a transverse sectional view 50 taken substantially upon the plane of line III—III of Fig. 1.

Figure 4 is an enlarged fragmentary transverse sectional view illustrating a portion of the waterproofing coating with the

adjacent concrete and earthy material at 55 its opposite surfaces, and

Figure 5 is a fragmentary elevational view of a portion of the coating material, different layers of which the material is composed being broken away at different 60 points so as better to illustrate the nature of the material.

Referring to the drawings for describing in detail the structure which is illustrated therein, the reference character L indicates 65 a shell, or former, which is provided at its lower end with a nose piece 1, the lower annular edge of the shell being received in a suitable recess 2 formed in the nose piece in such manner with the different sections 70 as 3, 4 and 5 of which the shell is composed are held in proper assembly.

This shell is constructed and is sunk into the earth in a manner substantially the same as has been shown and described in 75 my pending application Serial No. 306,134, filed June 23, 1919.

Within the shell is arranged the waterproof coating, or jacket G. This jacket is in the form of a bag closed on all its sides 80 and at its bottom and being open only at its top end for receiving the concrete material 6 which may be emptied thereinto after the jacket is in place within the shell.

The waterproofing material, of which the 85 jacket is formed, is preferably composed of a plurality of layers of different materials arranged, for instance, as illustrated in Figs. 4 and 5, wherein the three distinct layers are illustrated as at 7, 8 and 9. The layer 90 7 is innermost and lies against the surface of the concrete material 6. The layer 8 is intermediate and the layer 9 is outermost. The intermediate layer 8 is preferably of soft, pliable and sticky material such as 95 asphalt or asphalt composition. It constitutes also the essential waterproofing element of the jacket and it is preferably non-hardening. The innermost layer 7 is preferably quite thin and more or less porous 100 so that the sticky material of the layer 8 may penetrate thru it to a greater or less extent and engage with and adhere to the concrete material. Thin paper of a coarse fibrous texture is well suited to this purpose 105 as it fulfills the above requirements and at the same time is sufficiently strong and durable to form an appropriate cover for

the inner surface of the layer 8 while the jacket is being handled and prior to the application of the concrete material. Woven cloth of suitable texture may be used if 5 preferred. It should be noted also that due to the porosity of the layer 7 portions of the concrete material may in some instances be forced thru the layer 7 and into direct engagement with the material of the layer 10 8 at different points.

The layer 9 is utilized as a protection to the outer surface of the layer 8. It serves as a support and foundation for the layer 8 at all times and protects the layer 8 from 15 harm. By its position upon the exterior surface of the layer 8 it stands to engage against the inner surface of the shell L during the formation of the pile and it provides a desirably strong, and yet yielding, 20 surface adapted to withstand the frictional strains imparted to it during the lifting out of the shell sections after the concrete material has been introduced. It also is capable of withstanding the distortional strains 25 to which it is subjected after removal of the shell by reason of the settling and expanding of the concrete material into the space left upon removal of the shell and by reason of the expansion into voids of 30 greater or less extent which may be present at different points in the adjacent surface of the earth. A strong, heavy fibrous paper is suitable for forming the layer 9 but other materials may be employed if desired such 35 as burlap, canvas or the like.

In some instances it is desirable to provide additional reinforcement for the jacket and this is shown herein as being present embedded in the material of the layer 8 of 40 the jacket. It is represented by the reference character 10 and is illustrated to consist of a layer of coarse woven material. Strips of thin sheet copper thus disposed have been found to be well suited to the 45 purpose. Altho the strips are preferably woven together, as illustrated, yet of course they may be otherwise arranged as preferred, or they may consist of other forms and kinds of metal, or of fabric. Being 50 entirely embedded within the material of the layer 8 this reinforcing material is effectively protected at all times against all exterior agencies and will last for an indefinite period.

55 In operating this invention the jacket may be placed within the shell either before or after the shell is driven into the earth. After the shell is driven and the jacket is in place the concrete material is then poured 60 into the jacket from above thus filling the jacket and pressing the outer surface of the layer 9 of the jacket tightly against the inner surface of the walls of the shell. The shell is then removed allowing the jacket 65 to spread a greater or less extent under the

weight of the concrete material. This action causes the concrete material to be brought into very intimate engagement with the layer 7 of the jacket and in fact with the material of the layer 8 thru the pores of 70 the layer 7.

Where a sectional shell is employed the shell is removed section by section and while this is of some advantage in reducing the strains upon the jacket, yet it is not to be 75 understood that this invention is limited to the use of a sectional shell. Non-sectional shells may be used, if desired.

The shells may be also of uniform diameter or they may be tapered as illustrated, according to preference.

Where the shell is formed within earthy material which is of suitable consistency to support the pile in pile shape during the hardening of the concrete material, the shell 85 may be removed, while the concrete material is yet plastic and unset so as thus to enable the pile to conform itself more accurately to the shape of the surrounding earth, but where the earthy material is not of the req- 90 uisite consistency, or where the pile is driven thru water, as for instance, in the bed of a stream or the like, the concrete material may be allowed to harden to a suitable extent before the removal of the shell. Or the shell 95 may be lifted only part way; that is, to a point where the lower end of the shell is still in solid earth and then allowed to remain until the concrete material has hardened. In this way the lower portion of the pile which is 100 within the solid earth is enabled to conform itself to the contour of the earth and yet the portion of the pile which extends upwardly into the water is held in proper form during the hardening process and the waterproofing 105 jacket is maintained and supported so that when the shell is finally removed the jacket is intact thruout, protecting the lower portion of the pile from the evil effects of the earth constituents and protecting the upper 110 portion of the pile from the watery constituents.

Piles constructed and waterproofed in accordance with this invention may be utilized in many instances where concrete piles have 115 heretofore been inefficient and impractical. They will be proof against the evil effects of many agencies which have heretofore rendered concrete piles unreliable. They will be proof against electrolysis, against mineral 120 attacks, and against the deteriorating action of salt water, etc. Metallic reinforcing rods, or bars, or metallic members of other qualities embedded in the concrete material for instance to be used as holding means for 125 superstructures and the like, will incidentally be protected.

The layer 9 of the jacket may in time be absorbed and disappear but yet the layer 8 will remain intact for many years.

As many changes could be made in this construction without departing from the scope of the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A waterproof jacket within which to mould a concrete structure, said jacket comprising a layer of sticky material and a layer of porous material arranged between the sticky material and the concrete material enabling penetration of the sticky material into engagement with the concrete material and vice versa.
2. A waterproof jacket within which to mould a concrete structure, said jacket comprising a layer of sticky material and a layer of porous material arranged between the sticky material and the concrete material enabling penetration of the sticky material into engagement with the concrete material and vice versa, and said jacket also including an outer layer arranged for supporting the sticky material.
3. A waterproof jacket within which to

mould a concrete structure, said jacket comprising a layer of sticky material and a layer of porous material arranged between the sticky material and the concrete material enabling penetration of the sticky material into engagement with the concrete material and vice versa, and said jacket also including an outer layer arranged for supporting the sticky material, together with a reinforcing element embedded within said sticky material.

4. A waterproofing material for concrete piles consisting of a layer of porous material, a layer of sticky material, and a supporting layer, together with a layer of reinforcing material embedded within said layer of sticky material.

5. A waterproof jacket within which to mould a concrete structure, said jacket having on its inner surface a layer of sticky material to be engaged by, and adhere to, the concrete material.

In testimony whereof I affix my signature in the presence of two witnesses.

MAURICE BLUMENTHAL.
